UNITED STATES PATENT OFFICE.

MARTIN TUFTY AND JOHN M. SCHOEDER, OF KENNEDY, NORTH DAKOTA.

HEADER ATTACHMENT FOR BINDER-EQUIPPED HARVESTERS.

1,119,898.

Specification of Letters Patent.

Patented Dec. 8, 1914.

Application filed November 22, 1913. Serial No. 802,396.

To all whom it may concern:

Be it known that we, MARTIN TUFTY and JOHN M. SCHOEDER, citizens of the United States, residing at Kennedy, in the county 5 of Hettinger and State of North Dakota, have invented certain new and useful Improvements in Header Attachments for Binder-Equipped Harvesters; and we do hereby declare the following to be a full, 10 clear, and exact description of the invention, such as will enable others skilled in the art to which it appertains to make and use the same.

Our invention has for its object to provide 15 a header attachment for binder-equipped harvesters, and, to this end, it consists of the novel devices and combinations of devices hereinafter described and defined in the claims.

Under certain conditions, it is very desirable 20 to use a binder in harvesting grain, and, under other conditions, it is desirable to use a header. As these two machines are constructed entirely independent one from 25 the other, very few farmers have both. By the use of our invention, the binder attachment of a harvester may be removed, at will, and our header attachment substituted therefor.

In the accompanying drawings, which 30 illustrate the invention, like characters indicate like parts throughout the several views.

Referring to the drawings, Figure 1 is a 35 rear end elevation of a harvester having incorporated therein our invention, some parts being removed and some parts being broken away, and the binder attachment being indicated by dotted lines; Fig. 2 is a 40 side elevation of the header attachment removed from the harvester; Fig. 3 is a longitudinal vertical section taken centrally through the header attachment; and Fig. 4 is a plan view of the same.

Of the parts of the harvester illustrated 45 for the purpose of this case, it is only necessary to note the main frame 1, bull wheel 2, grain wheel 3, platform 4, platform conveyer 5, and the inclined elevator arranged 50 to receive from the platform conveyer and comprising coöoperating upper and lower endless conveyer belts 6 and 7, respectively.

This elevator extends transversely of the machine, and its upper or delivery end terminates directly above the bull wheel 2. 55

The binder attachment is indicated, as an entirety, by the numeral 8, with the exception of the driven sprocket 9.

The driving connections from the bull wheel to the platform conveyer, elevator 60 and binder attachment are as follows:—A sprocket chain, not shown, runs over a large sprocket wheel 10 on the axle of the bull wheel 2 and a relatively small sprocket wheel 11, on one end of a shaft 12, journaled in bearings 13 on the frame 1. On the other end of the shaft 12 is a beveled gear 14 which meshes with a beveled pinion 15 on a counter shaft 16, journaled in bearings on the frame 1. A sprocket chain 17 70 runs over the sprocket wheel 9 and alined sprocket wheels 18 and 19 on the counter shaft 16 and rollers 7^a of the conveyer belt 7, respectively. The section of the sprocket chain 17 between the sprocket wheel 18 and 75 the upper sprocket wheel 19 is indicated by dotted lines. In actual usage, a suitable belt tightener for the sprocket chain 17 will be provided. The platform conveyer 5 is driven from the lower roller 7^a by an intermediate spur gear 20, journaled in bearings on the platform 4 and meshing with spur pinions 21 on the inner roller of the platform conveyer 5 and the lower roller 7^a. To the upper ends of the sides of the 80 frame of the conveyer belt 7 is secured a pair of laterally spaced metallic plates 22, having vertically alined hinge lugs 23, to which the so-called wings of the harvester, not shown, are secured. As is well known, 85 these wings are provided for guiding the grain from the elevator to the binder. Journaled in the plates 22, between the delivery end of the elevator and the binder, is a roller 24 which is driven from the upper 90 roller 7^a by an intermediate gear 25 journaled to one of the plates 22 and meshing with pinions, not shown, on the rollers 7^a and 24. The parts thus far may be of the 95 standard or any desired construction. 100

In applying our invention to a binder-equipped harvester, the binder attachment is removed therefrom and the cutting mechanism elevated, so as to cut only the

heads of the grain. The improved header attachment comprises an upwardly inclined delivery belt or apron 26, arranged to form a continuation of the conveyer belt 7 and to receive the heads of grain delivered thereby. From the delivery belt 26, the heads of grain are deposited in a wagon box or other receptacle driven along one side of the harvester, as is customary with all headers.

The delivery belt 26 is mounted on upper and lower rollers 27 and 28, respectively, journaled in the laterally spaced sides of a frame 29. Said sides are connected by transverse bars 30 extended between the upper and lower sections of the delivery belt 26. To the inner faces of the sides of the frame 29 are secured longitudinally extended rails 31, which support the upper or operative section of the delivery belt 26. The frame 29 is detachably secured to the frame of the conveyer belt 7 by depending lugs 32, rigidly secured to the lower ends of the sides of the frame 29 and insertible through the lugs 23. Oblique rods 33 are provided for supporting the outer end portion of the frame 29 from the machine frame 1. The upper ends of the rods 33 are pivotally secured to the sides of the frame 29, and their lower ends are provided with bifurcated heads 34, the prongs of which embrace the frame 1. The delivery belt 26 is driven by the sprocket chain 17, which runs over a sprocket wheel 35 on the roller 27. It is important to note that the sprocket wheels 9 and 35 are so located that the sprocket chain 17 can run over either thereof without changing the operative length thereof. To remove the header attachment, it is only necessary to remove the sprocket chain 17 from the sprocket wheel 35 and lift the device bodily from the harvester.

A hood 36 is secured to the upper longitudinal edges of the sides of the frame 29 and extends over substantially three-fourths of the entire operative surface of the delivery belt 26. The space between the upper surface of the belt 26 and the hood 36 affords an accumulation chamber 37, the purpose of which will presently appear. Pivotally secured to the delivery end of the frame 29 is a horizontally extended receptacle 38, eccentrically located, with respect to the roller 28, and affording a gate at the delivery end of the accumulation chamber 37. The outer end of the hood 36 is curved laterally downward and extends into the gate 38, as best shown in Fig. 3. An operating lever 39 is provided for oscillating the gate 38 and is pivotally mounted, at its lower end, on the trunnion of the roller 27. A long link 40 connects the intermediate portion of the lever 39 to the gate 38.

The purpose of the accumulation chamber 37 and gate 38 is to hold the heads of

grain and prevent the discharge thereof while the machine is turning corners. It often happens that, while the machine and wagon for receiving the heads of grain are turning corners, they get out of proper relation, one to the other, so that considerable grain is lost by falling on the ground.

What we claim is:—

1. In a harvester, the combination with an endless conveyer belt, of a hood overlying a part of said belt and extending to the delivery portion thereof, to afford an accumulation chamber, and a gate at the delivery end of said belt.

2. In a harvester, the combination with an endless conveyer belt, of a hood overlying a part of said belt and extending to the delivery portion thereof, to afford an accumulation chamber, and a pivoted receptacle, affording a gate at the delivery end of said belt, for holding the grain delivered from said belt.

3. In a harvester, the combination with an endless conveyer, of a hood overlying a part of said belt and extending to the delivery portion thereof, to afford an accumulation chamber, a pivoted receptacle, affording a gate at the delivery end of said belt, for holding the grain delivered from said belt, and means for oscillating said gate.

4. A harvester having a main frame, a bull wheel, driving connections from said bull wheel, including a sprocket wheel, a platform conveyer, an inclined endless conveyer belt, arranged to receive from said platform conveyer and extending over said bull wheel, and sprocket wheel equipped rollers, on which said inclined conveyer is mounted, in combination with a delivery conveyer, arranged to receive from said inclined conveyer and to deliver to one side of said harvester, of upper and lower rollers on which said delivery conveyer is mounted, a sprocket wheel on said lower roller, a sprocket chain arranged to run over all of said sprocket wheels, a hood overlying a part of said delivery conveyer and extending to the delivery portion thereof, to afford an accumulation chamber, and a gate at the delivery end of said delivery conveyer.

5. A harvester having a main frame, a bull wheel, driving connections from said bull wheel, including a sprocket wheel, a platform conveyer, an inclined endless conveyer belt, arranged to receive from said conveyer belt and extending over said bull wheel, and sprocket wheel equipped rollers on which said inclined conveyer is mounted, in combination with a delivery conveyer, arranged to receive from said inclined conveyer and detachably secured to the frame thereof, of upper and lower rollers on which said delivery conveyer is mounted, a sprocket wheel on said lower roller, a sprocket chain arranged to run over all of said sprocket

wheels, a hood overlying a part of said delivery conveyer and extending to the delivery portion thereof, to afford an accumulation chamber, a pivoted receptacle affording a gate at the delivery end of said delivery conveyer, and lever connections for oscillating said gate.

In testimony whereof we affix our signatures in presence of two witnesses.

MARTIN TUFFY.
JOHN M. SCHOEDER.
